[57] CLAIM

The ornamental design for the emergency microfilmed medical and identification record, shown and described.

DESCRIPTION

FIG. 1 is a top plan view of an emergency microfilmed medical and identification record showing my new design.

FIG. 2 is a front elevational view thereof. The rear elevational view is identical to the front elevational view.

FIG. 3 is a left side elevational view thereof. The right side elevational view is identical to the left side.

FIG. 4 is a bottom plan view thereof.

FIG. 2

FIG. 1

FIG. 3

FIG. 4
